JAMES JENKINSON, OF WILLIAMSBURG, NEW YORK.

Letters Patent No. 97,515, dated December 7, 1869; antedated December 4, 1869.

SAD-IRON HEATER.

The Schedule referred to in these Letters Patent and making part of the same.

To all whom it may concern:

Be it known that I, JAMES JENKINSON, of Williamsburg, Kings county, New York, have invented a new and useful Improvement in Heating Sad-Irons; and I do hereby declare that the following is a full, clear, and exact description thereof, which will enable others skilled in the art to make and use the same, reference being had to the accompanying drawings, forming part of this specification, in which—

Figure 1 is a detail sectional view of my improved sad-iron and stand.

Figure 2 is a top view of the stand.

Similar letters of reference indicate corresponding parts.

My invention has for its object to furnish an improvement in heating sad-irons with kerosene-lamps, gas-burners, &c., by means of which the sad-irons may be readily and conveniently heated; and

It consists in the construction of the sad-iron, as hereinafter more fully described.

A represents a lamp, about the construction of which there is nothing new.

B is the stand, consisting of a plate, b^1 , with three or more legs, b^2 , at such a distance apart as to receive the body of the lamp A between them.

In the plate b^1 of the stand B, is formed a hole or holes, with an upwardly-projecting tubular flange, b^3 , surrounding the burner or burners.

The stand B should be formed with as many flanged holes as it is desired to heat sad-irons at the same time, and an equal number of burners should be used.

C is the sad-iron, which is made with a hole extending longitudinally through it, from heel to point, the

rear end of said hole being so formed as to fit upon the tubular flange of the stand B, the sad-iron itself thus serving as a lamp-chimney, and, at the same time, receiving the full force of the flame of the lamp.

D is the handle, the rear arm of which is formed with a hook, to hook into an ear formed upon the body C of the said sad-iron.

The forward arm has a hook-lever, d' , pivoted to its forward side, which hooks into an ear formed upon the sad-iron C.

The upper end of the hook-lever d' is provided with a pin, which enters a socket in the handle D, in which socket is placed a coiled-wire spring, by the elasticity of which the upper end of the lever-hook is held forward, to prevent the handle from becoming accidentally detached.

I claim as new, and desire to secure by Letters Patent—

1. The sad-iron C, having the tapering longitudinal hole directly through it, from heel to point, and provided with the rebate at its base, so as to be applied to a heater, in the manner herein set forth and shown, for the purpose specified.

2. In combination with the above, the detachable handle D d' , as herein described, for the purpose specified.

The above specification of my invention signed by me, this 17th day of March, 1869.

JAMES JENKINSON.
